FRITZ WETTSTEIN, OF TORONTO, ONTARIO, CANADA, ASSIGNOR TO AKTIEBOLAGET VAPORACKUMULATOR, OF STOCKHOLM, SWEDEN, A CORPORATION OF SWEDEN.

STEAM PLANT.

Application filed June 11, 1925. Serial No. 36,355.

The purpose of my invention is to provide a steam plant with an accumulator for hot water and automatic control means in connection therewith, to permit the generation of steam in boilers independently of steam consumption or hot water consumption; to store the surplus of steam generated in the form of hot water in a hot water accumulator, and to regulate a condensing medium for the surplus steam, in a manner such that the pressure in boilers is maintained substantially constant.

A further object of my invention is to control a cold water supply to a device wherein the cold water condenses steam in response to steam pressure, so that the actuating pressure is maintained constant.

My invention further aims to store surplus energy in a plant in hot water, and use the hot water for feeding boilers, or the like purposes.

My invention is illustrated by means of the accompanying drawing, in which reference character 1 represents a steam boiler which may be of any type, and fired in any way, whether by coal, oil, pulverized fuel, waste gases or exhaust gases. Steam passes from boiler 1 to conduit 2, and into a conduit 3, from which a motor 4 is supplied, the motor, in the case shown, consisting of a condensing turbine controlled by any desired regulating means, as for example, a centrifugal governor 5. Reference character 6 designates a condenser for the turbine from which the condensate passes to hot well 7. From hot well 7, water is drawn through conduit 8 by centrifugal pump 9, which may be controlled in any desired way, or may be operated at constant speed. Centrifugal pump 9 forces water through conduit 10 into a device, wherein steam and cold water are mixed, and which, since it operates much as a feed heater, I will give it that designation.

Feed heater 11 may be of any form, and for purposes of illustration, I have shown a feed heater of the tray type, wherein the water falls successively over trays 12, thus affording large surface for condensation of steam. Steam is supplied to the heater 11 from conduit 3.

Reference character 14 designates a hot water accumulator, which is supplied with hot water formed by mixture of steam and water in feed heater 11, and which supplies

water to boiler 1 through conduit 15. I prefer to arrange the hot water accumulator above the boiler 1, so that water can flow by gravity into the boiler, since no pump is then needed to pass water into the boiler, whereas, if the accumulator is arranged at the same or a lower level than the boiler, it is necessary to have a pump between the accumulator and the boiler. Any means of controlling the flow of water from the accumulator to the boiler may be employed. For sake of illustration, I have shown a valve 16 controlled by a float 17 in the boiler. Steam conduit 18 affords communication, with the help of conduits 2 and 3, between the steam space of the boiler and the steam space of the accumulator, so that water will readily flow from the accumulator into the boiler when valve 16 is open.

Furthermore, by means of conduit 18, steam can be supplied from the accumulator to turbine 4 in case of peak loads. In this case, the temperature of the water will not remain constant as is planned in the normal operation of my invention, but the temperature and pressure will fall in order to flash the requisite steam for the peak.

Inserted in conduit 10 is a valve 19, which may be of any desired construction, but is to be arranged so that it will open on increase of actuating pressure, and decrease the flow through the same upon decrease of actuating pressure, whereby the actuating pressure is maintained constant. This is illustrated in the drawing by having actuating pressure acting through tube 20 act on the lower side of piston 21, on the upper side of which a spring 22 acts. The valve is arranged with its discs in relation to the valve openings, so that upward movement of piston 21 increases the flow through the valve. The actuating pressure is the pressure in conduit 2, which is to be maintained constant or substantially constant, except in such cases as the accumulator may act as a peak load equalizer by giving off steam. Valve 19 operates to control a supply of water operating to condense generated steam, so that a constant pressure in the conduit to which tube 20 is connected is maintained.

The operation of the arrangement is as follows:

Suppose, with all parts in normal operation, steam passing to the turbine 4, condensate passing to hot well 7, and water

passing through conduits 8 and 10 into feed heater 11 and condensing steam therein, thus preparing hot water which passes through conduit 23 into the accumulator 14, and 5 water being led to the boilers as required through conduit 15, the pressure in conduit 2 rises, due, for example, to increased supply of heat to the boiler, for example, by an increased supply of waste gases, or due to 10 decreased consumption of turbine 4. Increase of pressure in conduit 2 causes an increased opening of valve 19 by lifting piston 21. This allows a greater flow of water through conduit 10, and consequently, 15 more steam is condensed in feed heater 11, more steam is drawn into the feed heater from conduit 3, and consequently the pressure decreases in conduits 2 and 3, so that by actuation of pressure through conduit 20, piston 21 becomes lowered due to the preponderance of force of spring 22 over the pressure under the piston, and the flow of water through conduit 10 is reduced to again give a desired value of pressure in 25 conduit 2.

The reverse operation wherein decrease of pressure in conduit 2 closes valve 19 more or less to decrease the supply of cold condensing water, so that less steam is condensed 30 and rise of pressure takes place to normal, will be readily understood from the above description.

25 designates a make-up conduit for hot well 7. 24 designates a hot water line 35 leading from accumulator 14, whereby water may be withdrawn from the accumulator for other purposes than boiler feeding.

As is obvious to those skilled in the art, 40 various changes can be made in the arrangement of parts without departing from the scope of the present invention. The consumers of the plant may be arranged in various ways, and it is not necessary to regulate the valve 19 in response to boiler 45 pressure.

The boilers need not ordinarily be regulated as to fire intensity but if the water rises too high in accumulator 14 or falls too low as indicated by gage glass 26 the 50 fires can be decreased or increased respectively.

Having thus described my invention, what 1 claim is:

1. In a steam plant, in combination, a boiler, a hot water accumulator situated higher than the boiler, a feed heater situated higher than the accumulator, a conduit to supply cold water to said feed heater, means in said conduit actuated by variations of 60 pressure of steam of boiler pressure and operating to increase flow through said conduit upon increase of pressure and decrease flow through said conduit upon decrease of pressure, open steam conduits connecting said boiler, said heater and said accumulator,

to maintain the same pressure of steam in the boiler, the heater and the accumulator means to conduct hot water from said feed heater to said accumulator and means to conduct water from said accumulator to 70 said boiler.

2. In a steam plant, in combination, a boiler, a hot water accumulator, a feed heater, a conduit to supply cold water to said feed heater, automatic means directly 75 responsive to changes of pressure in said boiler operating to increase flow through said conduit upon increase of boiler pressure and decrease flow through said conduit upon decrease of boiler pressure, means to 80 conduct steam from said boiler to said feed heater, means to conduct hot water from said feed heater to said accumulator and means to conduct water from said accumulator to said boiler, the steam conducting 85 means being open to cause the same steam pressure to prevail in the boiler, heater and accumulator.

3. In a steam plant, in combination, a boiler, a hot water accumulator situated 90 above said boiler, a feed heater situated above said accumulator, a conduit to supply cold water to said feed heater, pressure actuated means in said conduit operating to increase flow through said conduit upon increase of boiler pressure and decrease flow through said conduit upon decrease of boiler pressure, means to conduct steam from said boiler to said feed heater, means to maintain the same pressure of steam in the boiler, the 95 heater and the accumulator, a conduit for flow of water from said feed heater to said accumulator, a conduit for flow of water from said accumulator to said boiler and automatic means to control flow through 100 the last mentioned conduit in response to variations of liquid level in the boiler.

4. In a steam plant, in combination, a boiler, a hot water accumulator, situated 110 above the boiler, a feed heater situated above the accumulator, a main steam conduit, conduits for connecting the boiler, the accumulator and the heater with said main steam conduit, and to maintain the same pressure of steam in the boiler, the accumulator and the heater, a cold water supply 115 conduit to supply cold water to said feed heater, pressure actuated means in said cold water supply conduit operating to increase flow of cold water through the same upon increase of pressure in said main steam conduit and decrease flow of cold water upon decrease of pressure in said main steam conduit, means to conduct hot water from said feed heater to said accumulator and 120 means to conduct hot water from said accumulator to said boiler.

In testimony whereof I affix my signature.

FRITZ WETTSTEIN.
